INTERMITTENT ATOMIZING SPRAY UNIT

Albert L. Edelstein, New York, and Brett S. Nichols,
William Dean Pulvermacher, and Fred E. Sandgren,
Mineola, N. Y., assignors, by mesne assignments, to
Albert L. Edelstein

Application August 24, 1954, Serial No. 31,986

Term of patent 7 years

(Cl. D16—2)

Fig. 1

Fig. 2

Fig. 4

Fig. 3

Fig. 1 is a perspective view of an intermittent atomizing spray unit, showing our new design;

Fig. 2 is a top plan view of the unit;

Fig. 3 is a front elevational view of the unit; and
Fig. 4 is a side elevational view of the unit.

We claim:

The ornamental design for an intermittent atomizing spray unit, as shown.
